(57) **CLAIM**

The ornamental design for a translucent ruler, as shown and described.

DESCRIPTION

FIG. 1 is a front elevational view of the first embodiment of a translucent ruler showing my new design;

FIG. 2 is a rear elevational view thereof;

FIG. 3 is a right elevational view thereof, the left elevational view being mirror image thereof;

FIG. 4 is a top plan view thereof, the bottom plan view being mirror image thereof;

FIG. 5 is a front elevational view of the second embodiment of a translucent ruler showing my new design;

FIG. 6 is a rear elevational view thereof;

FIG. 7 is a right elevational view thereof, the left elevational view being mirror image thereof; and,

FIG. 8 is a top plan view thereof, the bottom plan view being mirror image thereof.

The shade lines on the ruler indicate that it is translucent.
